UNITED STATES PATENT OFFICE.

NORMAN T. MILLS, OF SAN FRANCISCO, CALIFORNIA.

WINDING-KEY FOR CLOCKS.

1,358,457.

Specification of Letters Patent.

Patented Nov. 9, 1920.

Application filed June 15, 1920. Serial No. 389,181.

To all whom it may concern:

Be it known that I, NORMAN T. MILLS, a citizen of the United States, residing at San Francisco, in the county of San Francisco and State of California, have invented new and useful Improvements in Winding-Keys for Clocks, of which the following is a specification.

This invention relates to improvements in clocks and more particularly winding keys of the type fixed to the winding stem.

In the majority of small clocks, the winding and setting stems and the winding key are so arranged and constructed that when the key is grasped and turned the thumb nail of the hand is likely to contact with and cause the accidental turning of the setting stem whereby the hands of the clock are moved into the wrong position. This is particularly due to the construction of the winding key, which key where adapted to be grasped is usually thick or of such construction that the thumb takes up too much room and the thumb nail is not clear of the setting stem.

The primary object of my invention is to provide simple and efficacious means for overcoming the above-noted objections in clocks and I accomplish this by reducing the thickness of the winding key so that the fingers will clear the setting stem when winding the clock.

Referring to the drawings:

Figure 1 is a rear elevation of a clock constructed in accordance with this invention showing the position of the fingers relative to the winding key so as to clear the winding stem.

Fig. 2 is a rear elevation of a clock of the type now in general use, showing the fingers grasping the winding key and disposed so that they are likely to contact with the setting stem.

Fig. 3 is a top plan view of the winding key of this invention.

Fig. 4 is a side elevation of the winding key.

Fig. 5 is a sectional view taken on the line 5—5 of Fig. 3.

Referring to the present embodiment of the invention, I have shown in the drawings a clock 1 of the alarm type having a central setting stem provided with a knurled head 2.

The clock is provided with main clock spring and alarm spring winding keys 3

and 4 respectively arranged in the customary manner on opposite sides of the setting stem head 2. As shown in Fig. 2 of the drawings, the clock 5 is the same as the one illustrated in Fig. 1, save that the winding keys 6 and 7 are of the type now in general use upon such clocks. I shall first describe keys now in general use. These keys are provided with flat body portions 8 riveted to the winding stems 9 and extending transversely of the stems. The body portions 8 are formed with outwardly extending parallel sides 10 which are spaced apart, as shown in the drawings, substantially equal to the width of the body portion 8. Keys of this type are so thick that in grasping them with the fingers after the manner illustrated in Fig. 2, and in turning said keys, the thumb nail is likely to come into contact with the knurled head of the setting stem 11 and cause said stem to be accidentally turned.

Now, referring to Figs. 1, 3, 4, and 5 in which I have illustrated my improved winding key, I form the keys such as the ones 3 and 4 of the body portion 12 corresponding to the body portion 8 of the old type of key and which is provided with a handle portion constituting side pieces 13. 80 These side pieces correspond to the side pieces or flanges 10 of the old type of key, but, instead of being extended outwardly and at right angles to the body portion, are pinched or bent close together as shown in 90 Figs. 1, 3, and 5, so that the handle portion of the key, that is, that portion of the key which is grasped by the fingers, is of considerably less thickness than the corresponding portion of the key shown in Fig. 2. 85 These side portions 13 extend or converge upwardly, as at 14, to a point intermediate of their upper and lower edges and are then pressed together, as particularly illustrated in Fig. 5. By pressing the side portions 13 together and forming a relatively thin portion to be grasped, I may substitute the keys of this construction for the keys of the old type such as shown in Fig. 2 and by so doing, providing for turning of the keys in 100 winding of the clock without causing the thumb nail to come into contact with the setting stem 2 as shown in Fig. 1. The pressing together of the sides, that is, the forming of the key with a relatively thin 105 portion to be grasped, does not interfere with the turning of the key inasmuch as the 110

same area is provided and gives adequate, if not better, purchase in holding the key, but the fingers are not required to be spread apart as far in holding this type of key as is the case with the old type.

The side portions 13 by being converged, as at 14 serve as a stop to prevent the fingers from being pushed in toward the back of the clock to such an extent that the fingers are likely to engage the setting stem. By reason of the fact that the winding key extends outwardly beyond the setting stem in the holding of the key to wind the clock, the fingers will clear the stem but where the fingers are inserted close to the inner end of the key, as would be the case were the portions 14 provided, said fingers would be likely, as above-described, to contact with the stem and cause it to be accidentally turned.

I claim:

1. A winding key for clocks comprising a body portion adapted to be attached to the winding stem and flanges extending from opposite sides of the body portion and being pressed together along their upper edges whereby the key is of less thickness along its upper side than at the body portion.

2. In combination with a clock having a stem, a winding key operatively associated with the clock and having the portion thereof to be grasped in winding of less thickness than the remainder thereof, whereby the thumb of the hand will clear said setting stem.

3. A winding key for clocks comprising a body portion adapted to be connected with a winding stem and flanges extending outwardly from opposite sides of the body portion and converging toward their outer edges so that their outer edges are pressed into engagement with one another, whereby the key is of less thickness at its outer edge than at the body portion.

4. In combination with a clock having a setting stem, a winding key operatively associated with the clock and having a portion thereof to be grasped of less thickness than the remainder thereof whereby the hand of the operator will not contact with the stem in winding the clock.

5. A winding key for clocks comprising a body portion and a handle portion extending outwardly from the body portion and being larger at its inner end than at its outer end whereby the larger portion serves as a stop for the fingers of the hand in grasping said key.

6. A winding key embodying in its construction a body portion adapted to be secured to the winding stem of the clock and side portions extending outwardly from opposite sides of the body portion, then converging with their outer edge portions pressed into close engagement with one another, said converging portions serving as a stop adapted to engage the ends of the fingers grasping the pressed together portion of said sides.

NORMAN T. MILLS.
